PLATE OR SIMILAR ARTICLE

Ryotaro Takeoka, 221 Kitayamoto-cho, Nishikasugai-gun,
Aichi-ken, Japan

Filed June 7, 1968, Ser. No. 12,260

Term of patent 7 years

Int. Cl. D7—01

U.S. Cl. D44—15

The figure is a plan view of a plate or similar article, showing my new design, a portion of the design being shown between dot and dash lines and a repeat portion being shown between dotted lines.

The plate is of a conventional configuration when viewed from the side and bottom thereof.

I claim:

The ornamental design for a plate or similar article, substantially as shown and described.
